UNITED STATES PATENT OFFICE.

JOHN K. LAPE, OF FORT WORTH, TEXAS.

LOCOMOTIVE NUMBER-PLATE AND HOLDER THEREFOR.

No. 893,526.

Specification of Letters Patent.

Patented July 14, 1908.

Application filed February 26, 1907. Serial No. 359,890.

To all whom it may concern:

Be it known that I, JOHN K. LAPE, a citizen of the United States, residing at Fort Worth, in the county of Tarrant and State of Texas, have invented new and useful Improvements in Locomotive Number-Plates and Holders Therefor, of which the following is a specification.

In operating locomotives, it is important that the locomotives and their tenders be correspondingly numbered and to follow out this practice, a considerable loss both as to expense and use of locomotives often results. For instance, in case of repairs such as mending a leaky tank, substituting new wheels or the like on the tender, it is necessary to temporarily throw the locomotive out of commission with its tender since both are correspondingly numbered, and in order to make these repairs, employees are required to work night and day and often Sundays so as to get the locomotive ready as quickly as possible and at the smallest possible expense. In some cases a tank will spring a leak at a point far remote from repair shops so that it is necessary to send a substitute locomotive to relieve the one in question at the expense of the necessary fuel and salaries of the engineer, fireman and conductor, and the engine so relieved, must be brought back to the shop for repair. Furthermore, it is the universal practice to paint numbers on the locomotive and tender, and as these soon become obscured by soot and dirt, the numbers have to be repainted about four times a year. The cost of painting alone, while an important item, is relatively small as compared with the income lost by the locomotive being idle while being painted.

The principal object of my invention is to provide removable number plates for the locomotive and tender so that when the latter is rendered unserviceable, the number plates of the locomotive can be taken out and others substituted to correspond with a new tender or vice versa. This change can be effected in a very short time and the locomotives are always ready for service. When the tank of a locomotive while out on the road and far from the repair shops springs a leak or otherwise becomes defective, it is merely necessary to send out another tank in a freight train to take the place of the defective one which is immediately attached to the locomotive. The importance of having the tender or tank numbered

to correspond with the engine or locomotive is manifest since trainmen are daily given orders to meet a certain train having an engine with a certain number, and as these trains often pass each other at high speeds, the men depend upon the figures on the tenders, as they are sufficiently large to be read while the trains are in motion, while those on the locomotive, which are comparatively small, cannot be conveniently read.

A further object of the invention is the provision of an enameled steel number plate for locomotives and tenders in which the numbers are colored white on a black background, thus enabling the numbers to be merely visible, and since the plates are enameled, they can be readily washed when required. The holders for the number plates are of such construction that the latter can be conveniently removed as occasion requires.

With these objects in view and others, as will appear as the description proceeds, the invention comprises the various novel features of construction and arrangement of parts which will be more fully described hereinafter and set forth with particularity in the claims appended hereto.

In the accompanying drawing, which illustrates one of the embodiments of the invention, Figure 1 is a side elevation of a locomotive and the tender therefor both provided with removable numbering devices. Fig. 2 is a partial rear elevation of the tender. Figs. 3 and 4 are sections on line 3—3 and 4—4, Fig. 1. Fig. 5 is a front elevation of the front number of the locomotive. Figs. 6 and 7 are respectively a vertical section and a rear view of the front number.

Similar reference characters are employed to designate similar parts throughout the several figures of the drawing.

Referring to the drawing, A designates a locomotive and B, the tender therefor. On the steam dome 1 of the locomotive is a number plate 2 removably arranged in a holder 3. In practice, a number plate is arranged on each side of the dome 1. On the two sides and rear of the tender B are number plates 4 arranged in holders 5. The number plates are pieces of steel coated with enamel and having suitable numbers thereon which are also of enamel. The number plates 4 are considerably larger than those on the locomotive mainly for the reason that the tender number plates are relied upon by the trainmen for ascertaining the number of

the locomotive while the latter is in motion. The holders 3 and 5 are preferably malleable iron castings of U-shape and are riveted to the sheet metal of the dome 1 and tender B.

5 Each holder has a recess 6 which forms a pocket for receiving the side and bottom edges of the number plate.

The front number plate for the locomotive preferably comprises a disk 7 mounted in a 10 ring 8 of angle iron cross-section that forms a holder therefor. On the rear of the plate 7 is a tripod-like frame or spider 9 to the outer end of which the plate and ring are riveted. The center of the frame 9 is provided with a 15 threaded stud 10 that screws into the front plate 11 of the locomotive, as shown by dotted lines in Fig. 6. By means of this threaded stud, the front number plate can be readily removed and another one substituted when necessary.

On the rear of the tender B, as shown in Fig. 2, a secondary number plate 12 is provided, which is arranged in the holder 13. This number plate and holder are preferably 25 of the same construction as the larger ones. This secondary number plate 12 is used for the purpose of enabling the mileage of the tender to be readily kept. The plate 12 has the original number of the tender and is 30 never removed. When the tender is assigned to a different locomotive, the large number plates 4 are removed and new ones substituted to correspond with the number of the locomotive. The secondary number 35 plate 12 is taken out and reversed so that the number will be turned back against the tender and the mileage of the tender from this point on will be recorded under the original number of the tender, and this number 40 can be always ascertained by looking at the secondary number plate. When the tender is supplied with new rolling stock, of course the original secondary number plate will be taken out and a new one substituted 45 to correspond with the large number plates.

When the tender becomes disabled, all

that is necessary is to detach the same from the locomotive and couple up another one and change the number plate on the locomotive while substituting new ones corresponding to the substituted tender or vice versa. Thus, it will be seen that the locomotive is never out of service for any considerable time.

From the foregoing description taken in 55 connection with the accompanying drawing, the advantages of the construction and of the method of operation will be readily apparent to those skilled in the art to which the invention appertains, and while I have 60 described the principle of operation of the invention, together with the apparatus which I now consider to be the best embodiment thereof, I desire to have it understood that the apparatus shown is merely illustrative and that such changes may be made when desired, as are within the scope of the claims.

Having thus described the invention, what I claim is:—

1. A locomotive and tender, and a plurality of removable number devices arranged on the locomotive and tender, one of the devices comprising a plate, a ring extending around the periphery of the plate, a spider 75 at the rear of the plate; fastenings securing the ring and spider together, and a member on the spider for removably attaching the same in position.

2. A number device comprising a plate, a 80 ring of angle iron cross-section, a spider at the rear of the plate, rivets for securing the spider and ring together with a plate between them, and a screw on the spider for removably attaching the same to an object. 85

In testimony whereof, I affix my signature in presence of two witnesses.

JOHN K. LAPE.
